BRAKE SHOE

Filed May 22, 1926

FIG. 3

FIG. 2

64
FIG. 5

A cross-sectional diagram of a semiconductor structure. It features a central contact layer (58) with a hatched pattern. Above this is a p-n-p-n junction structure with a hatched pattern. The top surface is a flat, textured layer.

INVENTOR
LUDGER E. LABRIE

Mr. W. McCombs
ATTORNEY

UNITED STATES PATENT OFFICE.

LUDGER ELIZE LA BRIE, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed May 22, 1926. Serial No. 110,832.

This invention relates to brakes and is illustrated as embodied in an internal expanding automobile brake. An object of the invention is to secure great strength in a shoe 5 utilizing inexpensive and readily formed parts by reinforcing an outer cylindrical band forming or carrying the brake-lining by means of a novel stiffening member, preferably of channel section, secured to the inner face of the outer cylindrical part or band. One advantage of this construction is that it permits the use of bands of different widths with the same stiffening parts, to secure different widths of brake shoes without unduly 10 multiplying the number of parts to be manufactured.

Other features of the invention relate to forming a channel section member, such as the stiffening member described above, so 15 that it projects beyond the end of the shoe to form a pair of spaced arms, to an improved means of forming extended bearings for pivots for the shoe, and to other novel 20 combinations of parts and desirable particular constructions which will be apparent 25 from the following description of one illustrative embodiment shown in the accompanying drawings, in which:

Figure 1 is a vertical section through the 30 brake just inside the head of the brake drum, and showing the shoes in side elevation;

Figure 2 is a partial section on the line 35 2-2 of Figure 1 showing the means for taking the braking torque;

Figure 3 is a section through one of the end shoes on the line 3-3 of Figure 1;

Figure 4 is a section through the center shoe on the line 4-4 of Figure 1; and

Figure 5 is a partial section on the line 40 5-5 of Figure 1 showing a pivoted connection between two of the shoes.

The brake selected for illustration includes a drum 10, at the open side of which there may be arranged a backing plate or 45 other suitable support 12 and within which are arranged the three shoes 14, 16, and 18 of the brake, shoes 14 and 18 preferably being identical and interchangeable.

Shoe 16 is shown anchored on a pivot 20 50 carried by backing plate 12 and passing through a relatively large opening 22 in shoe 14, while shoes 14 and 18 are both pivotally connected to shoe 16 by means of pivots 24 and 26. The shoe may be applied by means

such as a double cam 28 arranged to force 55 shoes 14 and 18 apart against the resistance of a return spring 30, the shoes 14 and 18, particularly the shoe 18, thereupon forcing the shoe 16 toward the drum against the resistance of an auxiliary return spring 32. 60 When the brake is not applied, the spring 32 holds the shoe 16 in an idle position determined by an eccentric adjustable stop 34 interlocking with a groove in the end of pivot 24 formed by a flange 36. The pivot 26 65 preferably has a relatively large head 36 slidably engaging the backing plate 12 and, if desired, cotter pins 40 may be provided in the ends of the pivot 26 and the pivot or anchor 20 to prevent axial movement of 70 the shoes.

Each of the end shoes 14 and 18 is formed of a cylindrical part or band 42, shown as being a section of hot-rolled stock, to which the brake-lining 44 is secured and which is 75 reinforced by a stiffening web formed of two sheet metal stampings 46 and 48 secured by welding or riveting back to back and having outer flanges 50 welded or riveted or otherwise secured to the inner face of the 80 band 42. Preferably the stampings 46 and 48 are stiffened by short flanges 52 at their inner edges, and I prefer to run a flange entirely around the edge of each of the stampings so that the flanges 50 and 52 form sections of such a continuous flange. It will be 85 observed that the stiffening web formed by stampings 46 and 48 may be used to form shoes of different widths by varying the width of the part or band 42. Where the 90 shoes 14 and 18 are mounted on the pivots 24 and 26, I prefer to weld or otherwise secure separate rings 54 to form extended 95 bearings for the pivots.

The center shoe 16 is also provided with a 95 hot-rolled section or the like forming a band or cylindrical part 56 carrying the lining 58, but the stiffening means in this case is in the form of a channel section member 60 welded or riveted or otherwise secured to 100 the inner face of the band 56 and whose sides 62 and 64 form a pair of spaced stiffening parts. I prefer to spin over the inner edges of the side flanges 62 and 64 to form short outwardly extending stiffening flanges 105 66. Where the pivot 24 engages the sides of the shoe 16, I prefer to secure separate rings 68 to the outer sides of the parts 62

and 64 to form extended pivot bearings. I also may provide similar rings 68 for the pivot 26 and the pivot or anchor 20. It should be noted that the side flanges 62 and 5 64 project a considerable distance beyond the end of the outer part or band 56 to form spaced arms offset within the curve of the shoe and preferably mounted on the anchor 20.

10 While one illustrative embodiment has been described in detail, it is not my intention to limit the scope of the invention to that particular embodiment or otherwise than by the terms of the appended claims.

15 I claim:

1. A brake shoe comprising two stiffening flanges extended to form a cylindrical section of fixed width integral with the flanges, in combination with a lining-carrying band 20 secured to the cylindrical section and of different width than said section.

2. A brake shoe comprising two spaced-apart stiffening flanges extended to form a connecting cylindrical section of fixed width 25 integral with the flanges, in combination with a lining-carrying band secured to the cylindrical section, said flanges projecting

beyond the end of the band as a pair of pivot arms.

3. A brake shoe comprising, in combination, a cylindrical band, and a channel-section part secured to said band and forming stiffening means therefor and having its sides extended beyond the end of said band to form a pair of projecting arms. 35

4. A brake shoe comprising, in combination, a cylindrical band, and a channel-section part secured to said band and forming stiffening means therefor and having its sides extended beyond the end of said band 40 to form a pair of projecting arms, said arms being provided with openings at their ends to embrace a pivot and with openings near the end of the band for the pivot of a shoe overlapped thereby. 45

5. A brake shoe comprising a pair of flanges formed with alined openings for a pivot, and having separate rings secured to the sides of the flanges about the openings to form extended pivot bearings. 50

In testimony whereof, I have hereunto signed my name.

LUDGER ELIZÉ LA BRIE.
